UNITED STATES PATENT OFFICE.

THOMAS H. SEELY, OF MALDEN, MASSACHUSETTS, ASSIGNOR TO UNITED SHOE MACHINERY CORPORATION, OF PATERSON, NEW JERSEY, A CORPORATION OF NEW JERSEY.

FORMING APPARATUS.

1,375,802.

Specification of Letters Patent. Patented Apr. 26, 1921.

Application filed October 17, 1918. Serial No. 258,597.

To all whom it may concern:

Be it known that I, THOMAS H. SEELY, a citizen of the United States, residing at Malden, in the county of Middlesex and 5 State of Massachusetts, have invented certain Improvements in Forming Apparatus, of which the following description, in connection with the accompanying drawings, is a specification, like reference characters on 10 the drawings indicating like parts in the several figures.

This invention relates to forming apparatus and particularly to those employed for molding such objects as leggings. 15 Heretofore work of this character has been accomplished, so far as I am aware, by employing male and female molds the co-operating pressure surfaces of which are partial developments of a form generally 20 corresponding in contour to the portion of the leg over which the legging is to fit, the separated edges of these pressure surfaces being usually about 180° apart, or by using a relatively small number of outer mold sec- 25 tions which are connected to move together. The first-mentioned arrangement tends to set the legging in an incorrect curve, the legging being at the end of the molding operation open or trough shaped, leaving it 30 dependent upon the fastening means to bring it to the proper form in use. Furthermore, in making either of these types of molds it is necessary to use great care to have the pressure surfaces equally spaced 35 from one another throughout to obtain uniform pressure over the entire area of material operated upon.

An object of the present invention is to furnish readily constructed means for approximating by the molding operation the 40 true shape of the legging. To attain this end, inner and outer molds are employed, the material or blank to be formed being placed about the inner, which is preferably 45 of leg shape and with which the outer mold co-operates through more than half its circumference. One of the molds, in the present instance the outer, consists of series of 50 independently movable sections, which are shown as also yieldable, each with a pressure surface conforming to the portion of the form with which it co-operates. This independence of movement and capability for yield insures sufficient uniformity of pres-

sure without requiring very perfect agree- 55 ment of form between the outer and inner molds. In the embodiment of the invention illustrated, a plurality of guideways radiate from the leg form, being arranged in a circumferential series, and in each guideway 60 is a longitudinal series of pressure sections moved toward the form by an actuating member, as a cam, which is common to the longitudinal series.

A further object of the invention is to so 65 actuate the mold sections that the pressure is applied to the best advantage without creating fullness over undesired portions of the material operated on. This may be accom- 70 plished by moving the sections successively rather than simultaneously. Preferably this successive movement is imparted circumferentially of the inner mold, first a 75 section or a longitudinal series of sections intermediate the ends of the series about the inner mold being actuated, and then the sections or longitudinal series at each side thereof. This relative movement may be obtained by the arrangement of the cams or 80 other actuating members for the sections.

Other features of my invention will be developed in the following description and claims, reference being had to the accompanying drawings, in which

Fig. 1 is a front elevation of a particu- 85 lar machine illustrating the invention;

Fig. 2 is a side elevation looking from the right, Fig. 1;

Fig. 3 is a partial elevation of the rear 90 end of the machine, with portions broken away;

Fig. 4 is a vertical section on the line 4—4 of Fig. 3;

Fig. 5 is a horizontal section on the line 95 5—5 of Fig. 1;

Fig. 6 is a vertical section on the line 6—6 of Fig. 2; and

Fig. 7 shows in perspective adjacent pres- 100 sure plates, considered circumferentially of the form.

Upon a base 10 are mounted front and rear end frames 12 and 14, respectively, connected by the tie rods 16 which support guide bars 18. Formed between adjacent bars are guideways 20, here shown as five in 105 number, which radiate in a circumferential series from an inner mold member 22. This member is furnished by a leg-form having

the contour of the calf and ankle portions of the leg. The form is supported by a horizontal spindle 24 fixed to the upper portion of the rear frame 14, it being free to move longitudinally so that it may be applied to or removed from the machine, enabling the operator to use forms of different dimensions. It is held against rotation on the spindle by a pin 26 projecting from the frame 14 and entering a recess 28 in the adjacent end of the form. The spindle 24 is preferably hollow to receive a heating device which I have illustrated as a steam pipe 30 extending through openings in spaced plates 32, 32. These plates support the pipes and being located at the ends of the form, tend to retain the heat where it is desired to utilize it. Each of the guideways 20 contains movable pressure members furnishing a sectional outer mold. The pressure members consist of relatively thin plates 34 situated side by side in contact with one another in continuous longitudinal series, the end plates of each series resting against the frames 12 and 14. Each plate may be recessed at 36 and have a circular opening of considerable diameter, shown at 38, serving in part to decrease the bulk of material. The edge 40 of each plate adjacent to the form is curved along its width and thickness to conform to the opposite form surface, the combined edges 40 providing the pressure surface of the outer mold. To render this sectional surface as nearly as possible continuous, the corners of the plates of adjacent longitudinal series overlap, being cut away at 42 to permit this.

Each pressure member is preferably formed in two portions, there being outside the inner, or pressure element proper, a plate 44 sliding in the ways 20. At the inner edge of each of the plates 44 is a series of recesses to receive helical springs 46, the ends of which project beyond the plate 44 and bear against the adjacent edge of the corresponding plate 34. The last-named plates are thus allowed to yield and accommodate themselves to irregularities of the surface against which they rest when pressure is applied to the plates 44. At the outer edge of each of the plates 44 is mounted an anti-friction roll 48, and with the rolls of each longitudinal series of plates, or those in each of the guideways 20, contacts a common actuating member, shown as a cam 50. Each cam is rotatably supported by spindles 52, 52 at its extremities, one of these spindles being journaled in the frame 12 and the other in a bearing plate 53 held in a circular opening in the frame 14 by a set screw 55. By removing any one of the plates 53, the corresponding cam may be drawn through the opening without disturbing the other portions of the frame. The cams are simultaneously rotated from an operating

shaft 54 journaled near the lower portion of the frames 12 and 14, the shaft being turned in the present instance by a hand wheel 56 fixed to its end outside the frame 12. Fast upon the shaft 54 outside the rear frame 14 is a pinion 58 meshing with a gear 60 upon the lowest or central cam spindle. Rotatable upon the frame 14 are idler gears 62, 62 which communicate the rotation through pinions 64, 64 fast on the spindle 75 of the next pair of cams at each side of the central cam. Similarly placed idler pinions 66, 66 further transmit the movement to the upper and outer pair of cams through gears 68, 68 fixed upon the cam spindles. 80

The cams for all the series of pressure members are preferably identical in form. Each has a portion *c*, which, when the anti-friction roll 48 of the outer portion of the pressure members is in contact with it, permits said members to rest clear of the form, to enable the operator to introduce the material. Beyond the portion *c* in the direction from which the cams turn, as indicated by the arrows in Figs. 1 and 6, is a portion *d* serving to force in the pressure members until they act upon the material surrounding the form. This pressure is maintained for a time by a portion *e* of each cam, and beyond this is a portion *f* which allows the pressure members to return to their normal positions with the anti-friction rolls again in contact with the portion *c*. The cams are so timed that the longitudinal series are caused to apply their pressures successively 90 about the circumference of the form. As shown, the lowest or central series comes first into action. Thereafter the series on each side are actuated simultaneously, and finally the two upper series are operated together. The extent of the portions *c* and *e* of the cams are such that all the series may simultaneously occupy their positions of withdrawal from the work and pressure against it. The return to normal of the 100 central series of pressure members may be under the influence of gravity, since their movement is vertical, and their weight will cause them, when released by the cams, to slide downwardly. The other pressure members, which have either little or no component of their weight effective to withdraw them from the form, have auxiliary means for this purpose. Through the openings 38 in the inner portions of the upper 110 series of pressure members extend rods 70 passing through slots 72 in the front and rear frames. Each rod is joined at its ends by links 74 to the nearly vertical arms of a pair of bell-crank levers 76 fulcrumed 120 outside the frames upon the spindles of the cams. The nearly horizontal arms of the levers 76 are connected by rods 78 passing through slots 80 in the frames. The weight of the rods 78 is sufficient, when the pressure 130

plates are free from the portions *e* of the cams, to withdraw the former through the levers and links to their normal positions, the rods 70 contacting with the outer edges 5 of the openings 38 to effect this.

In the use of the apparatus for molding a blank of leather or like material to produce a legging, the operator places the blank B (Fig. 6), properly tempered, about the 10 form 22, introducing it through the opening 25 in the front frame. The blank is preferably surrounded by a sheet *b* of leather or other material to prevent the impressions which might be produced by the edges of 15 the pressure members from showing in its surface. The blank and protective sheet are together drawn about the form with their edges in proximity to one another above the end frames, as appears in Fig. 6. Then the 20 operator, by rotating the hand wheel 56 in the direction of the arrow in Fig. 1, causes the cams to bring the portions *e* opposite the anti-friction rolls. The lowest intermediate series of pressure members is thus 25 first brought into contact with the material, acting upon a continuous band along the central portion. Because of the contour of their edges, the members furnish a pressure surface correctly shaped from the form 22, 30 and their independence of movement and yieldability cause them to adapt themselves to irregularities of the surface acted upon and thus exert a substantially uniform pressure throughout. After the central band is 35 thus brought under pressure, the members at each side are moved by their cams against the material, and then the remaining or upper series of pressure members are similarly actuated. In this way the blank is 40 gradually pressed out from its center toward its free edges, so that no fullness or irregularities are produced, as might be the case if pressure were applied simultaneously between opposite surfaces not properly 45 spaced from one another, or if pressure members nearest the free edges of the blank were brought into action before the intermediate members. The blank is then held 50 under pressure and under the influence of the heat from the pipe 30 by maintaining the portions *e* of the cams in contact with the anti-friction rolls 48 until the material has acquired a more or less permanent set. It will be noted that the pressure upon it 55 is over a considerable portion of its circumference, this being about 270°. As a consequence, the material acquires substantially the curvature of the form, or is, when removed from the apparatus, practically of 60 the contour of the leg to which it is to be applied. After the material is thus set, the pressure members are released by turning the hand wheel to bring the portions *e* of the cams beneath the anti-friction rolls. This 65 frees the material, which may be withdrawn

through the frame opening 25, the apparatus being now ready for action upon another blank.

Having fully described my invention, what I claim as new and desire to secure by Letters Patent of the United States is:—

1. In a molding apparatus, an inner and an outer mold, one of said molds including plural series of sections, and means for actuating said series in different time relation. 75
2. In an apparatus for forming leggings and the like, an inner mold about the circumference of which the material to be molded is placed, and an outer mold for contact with the material about more than half the circumference of the inner mold, and including sections movable independently in the molding operation. 80
3. In a molding apparatus, an inner and an outer mold, one of said molds including a series of yieldable sections movable independently into co-operation with the other mold. 85
4. In a molding apparatus, an inner and an outer mold, one of said molds including plural series of sections, and means for successively moving the sections by series. 90
5. In a molding apparatus, an inner and an outer mold, one of said molds including a series of sections, means for successively moving said sections, and means for oppositely moving the sections. 95
6. In a molding apparatus, an inner and an outer mold, one of said molds including a series of independently movable sections, 100 means including gearing for moving the sections toward the associated mold, and means for withdrawing the sections from the said mold.
7. In a molding apparatus, an inner and an outer mold, one of said molds including a series of overlapping sections. 105
8. In a molding apparatus, an inner and an outer mold, one of said molds including sections extending in series circumferentially and longitudinally along the companion mold. 110
9. In an apparatus for forming leggings, a leg-form, and a series of pressure members relatively thin in the direction of the 115 series and having surfaces co-operating with and conforming to said form.
10. In an apparatus for forming leggings, a leg-form, and series of pressure members extending along the form in a plurality of 120 directions and having surfaces co-operating with and conforming to said form in both directions.
11. In an apparatus for forming leggings, a leg-form, and pressure members arranged 125 in a series longitudinally of the form and having their pressure surfaces curved circumferentially of said form.
12. In an apparatus for forming leggings, a leg-form, and movable pressure members 130

- arranged in a series longitudinally of the form and having their pressure surfaces curved circumferentially of said form, the adjacent members of the series moving in 5 contact with one another.
13. In an apparatus for forming leggings, a leg-form, and molding members arranged in a plurality of series each extending longitudinally of the form.
- 10 14. In an apparatus for forming leggings, a leg-form, and pressure members arranged in a plurality of series each extending longitudinally of the form, the members of adjacent series overlapping one another.
- 15 15. In an apparatus for forming leggings, a leg-form, and pressure members arranged in plural series circumferentially of the form.
16. In an apparatus for forming leggings, 20 a leg-form, movable pressure members arranged in a series circumferentially of the form and embracing it for more than half its circumference, and means contacting with each pressure member to move it toward the form.
17. In an apparatus for forming leggings, a leg-form, pressure members arranged in a series, and means for moving the members successively.
- 30 18. In an apparatus for forming leggings, a leg-form, pressure members arranged in a series, and means for moving the members successively, an intermediate member being first operated.
- 35 19. In an apparatus for forming leggings, a leg-form, pressure members arranged in a series, and means for moving the members successively, an intermediate member being first operated and then a member at each 40 side thereof.
20. In an apparatus for forming leggings, a leg-form, pressure members arranged in a plurality of series each extending longitudinally of the form, means for operating the 45 members of each series simultaneously, and means for operating the series of members successively.
21. In an apparatus for forming leggings, a leg-form, and pressure members arranged 50 in plural series circumferentially of the form and being curved to conform thereto.
22. In an apparatus for forming leggings, a leg-form, and pressure members arranged in a series circumferentially of the form, 55 adjacent members of the series overlapping one another.
23. In a forming apparatus, a leg-form, a plurality of guideways extending therefrom, and a molding member movable in each 60 guideway and coöperating with the form.
24. In a forming apparatus, a leg-form, a plurality of guideways extending therefrom, and a plurality of molding members arranged in each guideway along the form and

being movable into coöperation with the 65 form.

25. In a forming apparatus, a leg-form, a plurality of guideways extending therefrom, and a plurality of molding members arranged in each guideway and having a mold- 70 ing surface conforming to the form.

26. In a forming apparatus, a leg-form, a plurality of guideways extending therefrom, a pressure member movable in each guideway and coöperating with the form, 75 and members operating to move the pressure members at different times.

27. In a forming apparatus, a leg-form, a plurality of guideways extending therefrom, a pressure member movable in each guideway and coöperating with the form, 80 and members operating first to move an intermediate pressure member and then members at opposite sides thereof.

28. In a forming apparatus, a leg-form, a plurality of guideways extending therefrom, a pressure member movable in each guideway and coöperating with the form, and members operating first to move an intermediate pressure member and then success- 90 ively a plurality of members at both sides thereof.

29. In a forming apparatus, a leg-form, a plurality of guideways extending therefrom, a plurality of molding members arranged 95 in each guideway along the form, and an actuating cam common to the molding members in each guideway.

30. In a forming apparatus, a leg-form, a plurality of guideways extending therefrom, 100 a plurality of pressure members arranged in each guideway along the form, and an actuating cam common to the pressure members in each guideway, the cams being arranged to first operate the cam of an intermediate series and thereafter cams at each side thereof.

31. In a forming apparatus, a leg-form, a plurality of guideways extending therefrom, a plurality of pressure members arranged 110 in each guideway along the form, an actuating cam common to the pressure members in each guideway, and means to rotate the cams to move series of members successively.

32. In a forming apparatus, a leg-form, a plurality of guideways extending therefrom, a plurality of pressure members arranged in each guideway along the form, an actuating cam common to the pressure members in 120 each guideway, and means common to plural pressure members for holding them in co-operation with a cam.

33. In a forming apparatus, a leg-form, a plurality of guideways extending therefrom, 125 a molding member movable in each guideway and coöperating with the form, each molding member consisting of a plurality

of portions, and springs between the portions.

34. In a forming apparatus, a leg-form, a plurality of guideways extending therefrom, and a plurality of independently yieldable molding members arranged in each guideway along the form and being movable into coöperation with the form.

35. In a molding apparatus, an inner and an outer mold, one of said molds comprising 10 a series of movable sections, and means comprising a series of cams for controlling the movement of said movable sections.

In testimony whereof I have signed my name to this specification.

THOMAS H. SEELEY.
